US0D1101060S

(12) **United States Design Patent** (10) **Patent No.:** **US D1,101,060 S**
(45) **Date of Patent:** **** Nov. 4, 2025**

(54) **SCOOTER**

(71) Applicant: **Razor USA LLC**, Cerritos, CA (US)

(72) Inventor: **Ian Desberg**, Cerritos, CA (US)

(73) Assignee: **Razor USA LLC**, Cerritos, CA (US)

(**) Term: **15 Years**

(21) Appl. No.: **29/949,667**

(22) Filed: **Jun. 27, 2024**

Related U.S. Application Data

(63) Continuation of application No. 29/791,880, filed on Feb. 15, 2022, now Pat. No. Des. 1,034,827.

(51) **LOC (15) Cl.** **21-01**

(52) **U.S. Cl.**

USPC **D21/423**

(57) **CLAIM**

The ornamental design for a scooter, as shown and described.

DESCRIPTION

FIG. 1 is a front perspective view of a scooter of my design;

FIG. 2 is a rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines are for the purpose of illustrating portions of the scooter that form no part of the claimed design.

1 Claim, 8 Drawing Sheets
